UNITED STATES PATENT OFFICE.

ANSON SEARLS, OF NEWARK, NEW JERSEY, ASSIGNOR TO THE SEARLS MANUFACTURING COMPANY, OF SAME PLACE.

WHIP-SOCKET.

SPECIFICATION forming part of Letters Patent No. 395,006, dated December 25, 1888.

Application filed November 15, 1887. Serial No. 255,256. (No model.)

To all whom it may concern:

Be it known that I, ANSON SEARLS, a citizen of the United States, residing at Newark, in the county of Essex and State of New Jersey, have invented a new and useful Whip Socket and Fastener, of which the following is a specification.

My invention relates to whip-sockets and the fasteners attaching the same to a carriage; and it consists in the construction of a whip-socket barrel and a lining that holds a series of springs through which the whip is properly inserted, held, and withdrawn; also, in the combination of a jaw pivoted to one end of a band that passes partly around the socket and is attached to a stationary jaw. The latter may also be adjustably attached to the band, by which the fastener may be adjusted to sockets of varying diameters and by the pivoted jaw to dash-rails of different sizes, all as herein more fully described.

Referring to the drawings, Figure 1 is a side view. Fig. 2 is a sectional view. Fig. 3 is a section at the line *x x*. Fig. 4 is a section at the line *z z*. Fig. 5 is a perspective view of the fastener. Figs. 6, 7, and 8 are detached views of the springs *C*, band *D*, and lining *B*.

The barrel *A*, preferably made of sheet metal, wood, or like material, is provided with a groove, *J*, internally at or near the top, and a wood bottom, *a*, preferably cone form internally. This bottom *a* and barrel *A* may be made in one piece of wood or other suitable material. The bottom is provided with a hole, *c*, through which the lining *B* passes and leaves an opening for the escape of dust or water.

The lining *B*, preferably of leather or other suitable material, is cut about the form shown to fit the interior of the barrel *A* and turn over at the top, as shown at *h*, and under at the bottom, as shown at *i*. It is provided with pockets *k*, that receive and hold the bottoms *e* of springs *C*. These pockets *k* are formed by cutting a flap out, turning it up from the hole *b*, and attaching or sewing them down to the lining, as shown by stitches *d*, or by any well-known means, leaving space to receive the springs *C*. A separate piece may be fastened to the lining *B* and serve the same purpose.

The springs *C* (one or more) are made about

the form shown, and the bottoms *e* inserted in pockets *k*, while the tops *M* are inserted in the groove *J*.

The lining *B*, made in tubular form, and 55 pockets *k* formed thereon, has springs *C* inserted in pockets *k*, and is then passed into the barrel *A*. The parts *i* are drawn through hole *c* and fastened at *i* by any well-known means. The top of lining *B* is then turned over and 60 pasted to or otherwise fastened to the outside of the top of barrel *A*.

It will be observed that the lining *B* is held from displacement when the whip is withdrawn by the fastened points *i* and springs 65 *C*; also, that the springs *C* are held up by the pockets *k* and held down by ends *M* engaging in groove *J* and laterally by the lining *B*, as shown in Fig. 4.

The springs *C* are held by the lining *B* with 70 pockets *k* and the groove *J*. They may be attached at *e* to the lining *B* by other well-known equivalent means, and thereby be held from slipping down. By these means I am enabled to combine the three parts in a simple and efficient manner, in which any whip 75 may be inserted, held, or withdrawn without marring it or injuring the parts, each part acting with the others to produce the result.

The fasteners, Fig. 5, are applied (one or 80 more) to any socket at any part of the barrel *A*, and are composed of a band, *D*, provided with a series of holes at *n* at one end, into which the screw-threaded jaw *F* is buckled or attached. By these holes *n* the fastener may 85 be lengthened or shortened, so that only one size of fastener may be adjusted to sockets of all diameters in general use. The other end of the band *D* passes through a loop in the jaw *E*, as shown, thereby forming a hinge or 90 pivot at *P*, on which jaw *E* may be swung sufficiently to adjust to all widths or thicknesses of dash-rails in common use. The construction of hinge *P* may be modified as desired to perform this function, yet be an equivalent.

The screw *Q* may pass through jaw *F* and engage in a threaded nut and produce the same result. To make the threaded hole in a separate piece or nut I hold to be equivalent to the threaded hole in jaw *F*.

The fastener is operated by adjusting it by

holes n to the proper lengths to fit the socket and attached thereto by screw Q , which is then run back until the jaw E opens on its pivot P far enough at r to admit the dash-
5 rail. The screw Q is then tightened until the jaws firmly embrace the dash-rail, and the band D is firmly drawn on the socket.

By this means I produce a fastener that is readily adjusted to whip-sockets of varying
10 diameters. The jaws also adjust to the dash-rail. One screw only to each fastener is used, and all the advantages of the vise and band-
fasteners are combined in a neat, efficient, and durable device.

15 Having described my invention, I claim as follows:

1. A whip-socket composed of a barrel having a contracted opening, c , at the bottom, and a lining suitably secured to the barrel at
20 the top and passing down through said opening c and secured by points i at the bottom of the barrel, as and for the purpose set forth.

2. A whip-socket barrel provided with a lining and a series of springs held therein by the lining, pockets, and grooves, as and for 25 the purpose set forth.

3. A whip-socket fastener composed of two jaws and a screw, and a band to which one of said jaws is pivoted, as and for the purpose set forth. 30

4. A whip-socket fastener composed of two jaws and a screw, and a band provided with holes n , to which one of the jaws may be adjustably attached, as and for the purpose set forth. 35

5. The combination of a band, D , a screw, and two jaws, E and F , hinged and adjustably attached to the band, as and for the purpose set forth.

ANSON SEARLS.
